UNITED STATES PATENT OFFICE.

WHITING ARNOLD, OF MANDARIN, FLORIDA.

BOAT-PROPELLED DEVICE.

No. 870,758.

Specification of Letters Patent.

Patented Nov. 12, 1907.

Application filed July 31, 1907. Serial No. 386,344.

To all whom it may concern:

Be it known that I, WHITING ARNOLD, a citizen of the United States, and a resident of Mandarin, in the county of Duval and State of Florida, have invented 5 certain new and useful Improvements in a Boat-Propelling Device, of which the following is a specification.

The object of my invention is to provide a new and improved boat propelling device, which is simple in 10 construction, permits of driving the vessel at high speed without requiring comparatively great power, dispenses with a long shaft connection between the motor and the propelling device, thus avoiding thrust 15 friction and whereby the paddle at all times works in dense and undisturbed water, thus causing greater speed.

In the accompanying drawings, in which like letters of reference indicate like parts in all the figures:— Figure 1 is a vertical side view of my improved boat 20 or propelling device mounted on a vessel, parts of which are broken away. Fig. 2 is an elevation of my improved propelling device.

A shaft 1 is mounted in suitable bearings 2 permanently secured and bolted on the vessel and this shaft 25 is connected with a sprocket wheel 3 which is rotated in the direction indicated by the arrow from a motor, such as a steam engine, and the like, or in fact this shaft can be rotated from the motor in any other suitable manner as the method and means of rotating the shaft 30 1 form no part of my present invention. The shaft 1 is provided with a crank 4, the cross piece of which passes loosely through lugs 5 projecting from a sleeve 6 bolted to a hollow or solid bar 7 which passes through said sleeve and to the lower end of which bar a paddle 35 8 is secured which extends transversely to the length of the boat and may be of any desired or suitable construction or size. The upper end of the bar 7 is pivotally connected with the upper end of stay rods 9 pivoted at their lower ends to suitable bearings 10 secured 40 on the deck of the vessel 11. The bar 7 of the paddle projects through a suitable well 12 in the hull of the boat.

The operation is as follows:—The shaft 1 is rotated

in the direction of the arrow shown in Fig. 1 whereby the crank 4 is moved to the right and downward. 45 This first swings the paddle 8 in the direction to the right and at the same time the paddle is gradually moved downward and as the crank passes in the said direction down beyond the horizontal through the plane of the shaft 1, the bar 7 and paddle 8 continue 50 their downward motion but at the same time are moved in the direction toward the stern of the boat and as by this time the paddle is fully immersed its great power pushes the boat forward in substantially the same manner as a boat is propelled by means of an oar. It 55 will be observed that as the crank shaft swings downward toward the right, the bar 7 passes into the opening between the two sides of the crank as otherwise the movements of the bar 7 could not take place and as the crank approaches the vertical position and extending 60 downward the bar 7 is gradually moved out from between the two arms of the crank. As the shaft 1 completes its rotation the crank arms move upward to the left thereby lifting the bar 7 into its highest position and so that the paddle in rising offers as little resistance 65 or back pressure as possible.

Having described my invention what I claim as new and desire to secure by Letters Patent is:—

1. The combination with a floating vessel, of a driving shaft provided with a crank, means for rotating said shaft, a bar pivotally connected with the crank, a paddle on the lower end of said bar, and a stay rod pivoted at its lower end to the vessel and at its upper end to the upper end of the bar carrying the paddle, substantially as set forth. 70

2. The combination with a vessel, of a driven shaft having a crank with two arms, means for rotating said shaft, a sleeve mounted pivotally on the crank between the arms, a bar passing through said sleeve and secured thereon, a paddle on the lower end of the bar and a stay rod pivoted to the upper end of the paddle carrying bar and to the vessel, substantially as set forth. 75 80

Signed at Jacksonville in the county of Duval and State of Florida this 15th day of June A. D. 1907.

WHITING ARNOLD.
